United States Patent Office

Des. 234,231

Patented Jan. 28, 1975

234,231

MOBILE SIGN

Louis Alfonso, 207 Churchill St.,
Pittsfield, Mass. 01201

Filed July 3, 1972, Ser. No. 268,866

Term of patent 14 years

Int. Cl. D20—03

U.S. Cl. D96—12 R

FIG. 1 is a front perspective view of a mobile sign showing my new design;

FIG. 2 is a rear perspective view thereof;

FIG. 3 is a top view thereof; and

FIG. 4 is a bottom view thereof.

I claim:

The ornamental design for a mobile sign, as shown and described.
